(57) **CLAIM**

The ornamental design for simulated flying game apparatus, as shown and described.

DESCRIPTION

FIG. 1 is a perspective view of the simulated flying game apparatus in accordance with the embodiment of the claimed design;

FIG. 2 is right side elevational view thereof;

FIG. 3 is top plan view thereof;

FIG. 4 is front elevational view thereof;

FIG. 5 is bottom plan view thereof;

FIG. 6 is left side elevational view thereof; and,

FIG. 7 is a rear elevational view thereof.
